UNITED STATES PATENT OFFICE.

HAROLD G. RANDALL, OF FELCHVILLE, VERMONT.

PUZZLE.

1,074,816.

Specification of Letters Patent.

Patented Oct. 7, 1913.

Application filed April 13, 1911. Serial No. 620,762.

To all whom it may concern:

Be it known that I, HAROLD G. RANDALL, a citizen of the United States, residing at Felchville, in the county of Windsor, State 5 of Vermont, have invented certain new and useful Improvements in Puzzles; and I do hereby declare the following to be a full, clear, and exact description of the invention, such as will enable others skilled in the art 10 to which it appertains to make and use the same.

This invention relates to a new and novel puzzle and has for its object to provide a device of this character which is simple in construction and may be cheaply manufactured.

A further object of the same is to so construct an article of this character that the same will be intricate to operate, but at the same time amusing.

With these and other objects in view, the invention consists in certain novel features of construction as hereafter shown and described and then specifically pointed out and claimed. The drawings illustrate a preferred embodiment of the invention.

In the drawings: Figure 1 is a top plan view of the device with the transparent cover removed. Fig. 2 is a transverse sectional view on line 2—2 of Fig. 1.

In constructing the device, a rectangular casing 1 is provided and may be formed from any suitable material. The casing 1 is divided into upper and lower compartments by a partition 2, the partition being formed 30 from wood, said partition being also rectangular in shape and fitted within the casing 1. Partition 2 is supported within the casing 1 by screws or the like placed at the points wherein the edges of the same contact with 35 the walls of the casing.

The upper surface of the partition is provided with a series of concentric grooves 3, and into which are secured a corresponding number of concentrically arranged annular 45 walls 4, said walls being formed from light sheet metal, but it will of course be understood that any other material may be used for this purpose.

The outermost wall is provided with an 50 entrance gateway 5, and through which a ball 6 is started upon its travel, said ball in its normal position being housed in a corner of the casing nearest the gateway 5. Each alternate wall 4 is provided with gateways 55 7, but none of said gateways being in registered relation, therefore compelling the ball

to travel in a semi-circular channel until a gateway is reached.

Arranged opposite certain of the gateways formed in the walls 4 are openings 8, said 60 openings extending through the partition 2 and have their lower outlets opening into the lower compartment or bottom of the casing. The openings 8 are so arranged in relation to the walls that they occupy approximately half of each channel wherein located. The terminus or central wall incloses the recess 9, said recess being the destination of 65 the ball when the puzzle has been properly manipulated. It will be noted that some of the points 8 are provided adjacent the walls 4 opposite to the gateways.

A glass covering 10 is provided, said covering being suitably secured to the side walls of the casing 1 and has its under surface 75 resting upon the upper edges of the walls, thereby preventing the ball from jumping said walls. It will be noted that the openings 8 are substantially semi-circular in cross-section, and present their inner curved 80 wall to each gateway opposite which they are located.

In operating the puzzle the casing is tilted so that the ball 6 passes through the gateway 5 and thence travels around the channel 85 into which said gateway leads until it reaches the gateway in the next inner wall, and passes into the next inner channel if said ball is successfully manipulated past the openings arranged opposite said gateway. 90 This operation is continued until the ball has traveled from one wall to the other until the same has reached the recess 9 located within the terminus wall. If during the operation the ball should drop through any 95 one of the openings the operator is compelled to manipulate the frame until the ball reaches the corner wherein the opening 11 is provided in the partition. The casing is then reversed until the ball passes from the 100 lower compartment through said opening 11 and to a point near the gateway 5, when the ball is again started upon its travel to complete the operation of the puzzle.

What is claimed is:—

A puzzle comprising a casing, a horizontal partition in said casing dividing the latter into lower and upper compartments, concentric rings arranged in and dividing the upper compartment into a series of endless 110 passages, said rings having staggered gateways through which adjacent passages com-

municate, and said partition being provided with openings affording communication between the lower compartment and said passages, said openings being located in pairs 5 with the openings of each pair disposed on opposite sides of the respective gate-ways and in adjacent passages respectively.

In testimony whereof, I affix my signature, in presence of two witnesses.

HAROLD G. RANDALL.
